UNITED STATES PATENT OFFICE.

JOHN P. DOWD, OF CLEVELAND, OHIO, ASSIGNOR TO THE BROWN HOISTING MACHINERY COMPANY, OF CLEVELAND, OHIO, A CORPORATION.

GRAB BUCKET.

1,415,812.

Specification of Letters Patent. Patented May 9, 1922.

Application filed July 19, 1921. Serial No. 485,819.

To all whom it may concern:

Be it known that I, JOHN P. DOWD, a citizen of the United States, residing at the city of Cleveland, in the county of Cuyahoga and State of Ohio, have invented certain new and useful Improvements in Grab Buckets, as to which the following is a sufficiently full, clear, and exact description to enable any one skilled in the art to which it relates to make and use the same without other particular information upon the subject.

The improvement relates more especially to grab buckets of the heavy duty type whose digging or spade members are controlled by a vertically oscillated crosshead. In this type the arms of the spade members are pivotally connected to the crosshead, and the spade members themselves are supported by means of links that are pivotally attached thereto and also to the bucket-frame or shell.

Buckets of the type and for the uses in question should combine a maximum of strength with a minimum of weight, and, also, have a constructive principle that permits of the easy and quick assembling of the parts, and, on need of replacements or repairs, of the ready dismantling of the same, by the separation of all the units involved. To the production of a grab bucket that is exceptionally characterized in these respects, the present invention is more particularly directed.

In the drawings Figure I is a side elevation of one-half of a bucket of the class referred to. It discloses a spade and one of the links as connected to the bucket frame and crosshead. Figure II is a front view on the lines 1, 1, in Fig. I, the links and bracing details being rendered in full lines, and, the bucket and spade parts, in section. Figure III is an enlarged view of the left hand details shown in Figure II.

2 indicates the bucket frame, 3 the usual spade or digging members, and 4 the spade-arms pivotally connected to the vertically oscillated crosshead 5, by a pin 6.

The foregoing parts being familiar to those acquainted with the art concerned, it is thought that no particular descriptions will be required herein except as such other special parts or members, whose co-relation with said parts in the mode I prescribe, make up the improvement claimed.

In such description, it is to be observed,

that, in the place of the heavy and unwieldy through-pins that have heretofore been employed to stiffen the spade-arms in certain bucket forms, and to support and serve as the axes of the link members in every form, I provide a distinct unitary link connection or piece 7, which performs all the functions of said through-pin combinations, but, at the same time, is lighter, and, more readily assembled, or, taken apart as occasion requires.

Said unitary piece or connection 7, is made up and consists of the following constituent members, namely: right and left links, 8, for each spade of the bucket, consisting of two hollow horizontally related trunnion or hub-members 8^a and 8^b, joined or otherwise connected together by a web-like section 8^c, which, in the drawings, has an I-shaped cross-section. The relative width of such web-section should be about half the length of the hubs, and its junction lines with the trunnion or hub members, should terminate near their ends, thereby leaving a sufficient portion of the hubs, toward their other ends, free to engage axle-bushings 15, and 16, on respectively, the frame 2, and the spade-arms 4. As a means of positively holding the links 8, 8, in their places, and at the same time, stiffening the spades 3, I suspend between said links, a frame-piece or bracing 9, made up of upper and lower horizontally arranged angles 10, duly riveted at their ends to cross-plates 11, 11 for the purpose. On the upper side and at each end of the bracing 9, an angle 12 having a pinhole 13 therethrough, is fastened, and, on the lower side of the same, at each end, bent bars 14, having pinholes 13^a, are located.

The diameters of said pinholes are the same as those of horizontal bolt holes in the trunnions 8^a and 8^b, and, the several parts of the bracing are so arranged, that, when the links 8 are in their operative places, said bracing 9 may be interposed between and against the trunnion members, with the holes 13, in the angles 12, in alignment with the holes in the trunnion members 8^a, and the holes 13^a, in the bent bars 14, in alignment and registering with the holes in the trunnion members 8^b.

At suitable points, respectively, on the bucket frame 2, and the spade-arms 4, holes are made to receive axle-bushings for the trunnions or hubs 8^a and 8^b. In practice

such bushings for the link-members in said buckets, should be of manganese steel, or other superhard material in order to resist the destructive action of dust from the limestone, coal, ore or sand with which such grabs are used. Said bushings are riveted respectively, to the bucket frame and the spade arms, and are denoted in the figures by 15 and 16. Their holes may, preferably, be given diameters one-sixteenth larger than the diameters of the trunnions 8^a and 8^b, in bearing within the same. Bolts 17 and 17^a, are provided to pass through the trunnions 8^a and 8^b, and the angles and bent bars 12 and 14, on the bracing 9, and, inasmuch, as there will be no binding strain on said bolts, but their sole function will be to hold the link-members and the bracing together, they may be given no larger diameter than is required for such purpose alone.

It will be understood, that in the improvement described, the only machining required is in boring the holes for said bushings in the bucket-frame and spade-arms, the holes 13 and 13^a being punched when the component parts of the frame-member or bracing 9 are punched for rivets.

In order to assemble said parts and members in their places as said unitary link-connection, the free ends of the trunnion 8^a and 8^b, on the right and left members of each pair of links, are duly journaled within the bushings 15 and 16 respectively, and the bracing 9 being then interposed between said pair, with the holes 13 and 13^a in alignment as hereinbefore explained, the bolts 17 and 17^a are respectively passed through the holes in said trunnions 8^a and 8^b, and the angles 12 and the bent bars 14. When now nuts 18 and 18^a are tightly screwed upon the inner ends of said bolts the pair of links 8 and 8, and the interposed frame-piece or bracing 9 will thereby become firmly joined together into and to form the unitary link connection designed.

The reverse of said process will, of course, be followed, whenever it is necessary to dismantle the portion of the bucket involved, for the replacement of the spades, or by reason of other exigencies of service, and, as it is thought with a minimum expenditure of time or effort.

It will be manifest that the idea upon which the improvement is based is not limited to the special application of the same shown and described. Such form is made up of certain particular parts whose assemblage as pointed out have proved highly satisfactory in practice, but the invention covered by the application, would equally be included in a link connection, although such parts were varied in shape or adaptation in order to realize the common end. Except as

especially claimed, the device could be made, for instance, with solid instead of hollow trunnion members, or instead of a trunnion member on both ends of the link, the link might be bifurcated at the lower end so as to pivotally engage the spade-arms between its forks, or, the bracing essential to hold the links against lateral displacement, might be removably connected to the links at points intermediate of the ends, without, in any such cases, departing from the idea or principle of the improvement as more broadly claimed herein.

What I claim and wish to secure by Letters Patent is:

1. In a grab bucket having spades with spade-arms pivotally connected to a cross-head therein, a unitary link-connection between the bucket frame and said spades, comprising the combination of links provided with trunnions at their upper ends, axle bearings for said trunnions on the bucket-frame, means for pivotally connecting the lower ends of said links to said spades, and means for securing said links against lateral movement when the ends of the links are in said bearing and pivoted relations, with, respectively, said frame and said spade, said means consisting of a frame-like member between, and removably connected to, said links so placed, all substantially as shown and described.

2. In a grab bucket, having a frame, a vertically oscillated crosshead centrally located therein, and a spade provided with oppositely related spade-arms pivotally connected to said cross-head, the combination of links having trunnions at the ends thereof journaled, respectively, in said frame and said spade, and a bracing member between and removably connected to said links, substantially as shown and described.

3. In a grab bucket having a frame, a vertically oscillated cross-head therein, and a spade provided with oppositely related spade-arms pivotally connected to said cross-head, the combination of axle-bearings on said frame and said spade, links having hollow trunnions at the ends journaled within said bearings, and a bracing-member between said links and bolted to the same by bolts passing through said trunnions and holes provided for the purpose, in said bracing-member, substantially as shown and described.

In witness whereof I have hereunto subscribed my name, at Cleveland, Ohio, this 13th day of July, 1921.

JOHN P. DOWD.
